UNITED STATES PATENT OFFICE.

JOHN MARX, OF NEW YORK, N. Y.

SASH-BALANCE.

SPECIFICATION forming part of Letters Patent No. 642,239, dated January 30, 1900.

Application filed May 27, 1899. Serial No. 718,492. (No model.)

To all whom it may concern:

Be it known that I, JOHN MARX, a citizen of the United States, and a resident of New York city, county and State of New York, 5 have invented certain new and useful Improvements in Sash-Balances, of which the following is a specification.

This invention relates to that class of windows having unbalanced sashes which are so 10 constructed that in lowering the sash a spring will be wound up which will subsequently assist in raising the sash. Thus the manipulation of the sashes is greatly facilitated.

The invention consists in the various novel 15 features of construction fully pointed out in the claims.

In the accompanying drawings, Figure 1 is a front elevation, partly in section, of my improved window; Fig. 2, a longitudinal section on line 2 2, Fig. 1; Fig. 3, a cross-section on line 3 3, Fig. 1; Fig. 4, a cross-section on line 4 4, Fig. 1; Fig. 5, a longitudinal section of part of the window; Fig. 6, a detail of the rod d^3 .

25 The letter A represents the frame of the window, of which B is the upper and C the lower sash. To the upper rail of the upper sash B there is secured a box b , within which there is free to turn a shaft b' . The ends of 30 this shaft extend laterally beyond the box and carry the fast ratchet-wheels b^2 , which engage racks a , secured to frame A. The shaft b' is surrounded by a spiral spring b^3 , one end of which is fastened to the box b , while its other end is fastened to the shaft.

35 When the sash is lowered, the shaft b' in rotating will wind up the spring, which is held under tension until the sash is raised, when the spring in unwinding will assist in drawing 40 the sash up. In this way the sash, though unbalanced, may be readily raised and lowered.

In order to hold the sash in any of its 45 positions and permit it to be manipulated from the bottom of the window, I employ the following construction: Secured to the inner side of the window-frame is a long slotted tube d , provided at suitable intervals with transverse notches or slots d' , which open 50 into a common upright slot d^2 . Within the tube d is contained an upright rod d^3 , which is reduced at its lower end and there sur-

rounded by a revoluble sleeve d^4 , which is provided with a transverse arm d^5 , carrying a drop-handle d^6 , Fig. 6. At its upper end the 55 rod d^3 terminates in an arm d^7 , embraced by the socket of a spring-actuated finger d^8 , which finger is adapted to engage a recess or perforation b^4 of box b .

To manipulate the sash, the handle d^6 is so 60 turned that the arm d^5 is brought into vertical alinement with slot d^2 , and the sash is raised or lowered to the desired elevation by means of the handle. The handle is then swung sidewise to introduce the arm d^5 into 65 the proper slot d' , and thus lock the sash in position.

Should it be desired to disconnect the sash from the elevating mechanism, this can be easily effected by withdrawing the spring-finger d^8 from recess b^4 when the arm d^7 is opposite the topmost slot d' (dotted lines, Fig. 5.)

The lower sash C is provided on its lower rail with a box c , in which turns the shaft c' , carrying the fast ratchet-wheels c^2 , that engage the 75 racks a' of frame A. The shaft c' carries on its center a grooved collar c^3 , engaged by an outwardly-extending spring-stud c^4 . At either side of collar c^3 the shaft is surrounded by a coiled spring c^5 , one end of which is attached to the box c , while its other end is attached to the shaft. If the stud c^4 is drawn out, the shaft c' is released, and the sash may be raised or lowered, the lowering of the sash causing a winding up of the spring, which assists in subsequently raising the sash, as previously described. When the stud c^4 is released, it will engage the grooved collar c^3 to hold the shaft c' against rotation, and thus lock the sash in position. 90

What I claim is—

1. In a window, the combination of a window-frame with a slotted and transversely-notched tube secured to the inner side thereof, a rod connected to the sash and embraced by 95 the tube, and a transverse arm revoluble upon the rod and adapted to engage either of the transverse notches and lock the sash at different elevations, substantially as specified.

2. In a window, the combination of a sash with a rotatable spring-actuated shaft carried thereby, gear-wheels fast on the shaft, racks engaged by the gear-wheels, a slotted and transversely-notched tube, a rod within 100

the tube, an arm revolubly secured to the rod and adapted to engage the notches, and a spring-finger that connects the rod to the sash, substantially as specified.

- 5 3. In a window, the combination of a sash with a rotatable shaft carried thereby, a grooved collar and gear-wheels fast on the shaft, racks engaged by the gear-wheels, a spring surrounding the shaft and adapted to 10 be wound and unwound by its rotation, and

a stud that is adapted to engage the grooved collar and lock the shaft, substantially as specified.

Signed by me at New York city, New York, this 26th day of May, 1899.

JOHN MARX.
